UNITED STATES PATENT OFFICE.

SAMUEL B. CALDWELL, OF OAKLAND, CALIFORNIA.

WASHING MACHINE.

Application filed April 7, 1921. Serial No. 459,320.

To all whom it may concern:

Be it known that I, SAMUEL B. CALDWELL, a citizen of the United States, and a resident of the city of Oakland, county of Alameda, 5 and State of California, have invented a new and useful Washing Machine, of which the following is a specification.

This invention relates to washing machines and more particularly to domestic 10 washing machines.

It is one of the objects of the present invention to provide a washing machine incorporating movable elements which are designed to reciprocate for the effective washing by compression and surging action of laundry pieces in a tub or tank. It is, in this 15 connection, a further object of the present invention to provide a mechanical washer in which the principal moving elements are 20 of light and simple construction, and therefore, operable with a small consumption of power.

Another object of the present invention is to provide a washing machine or apparatus 25 incorporating a cover or top for the tank or tub of the apparatus, and mounting upon the tub top the mechanically operable washing means. By arranging the washing elements and driving mechanism thereof upon 30 a removable top, it is possible to uncover the tank or wash tub by simply tipping the top upwardly and therefore permitting ready insertion and removal of the pieces of laundry into and from the tub.

35 Another object of the invention is to provide an organized washing machine unit adapted to be mounted bodily upon a cover of an ordinary domestic, installed wash tub and which mechanism may be sold in conjunction with wash tubs to be installed practically without any change in the construction and design of the laundry or wash tub.

It is a further object of the invention to 45 provide an organized washing machine that can be applied to wash tubs of various sizes, shapes and kinds of construction and material and which washing machine can be bodily applied to and bodily removed from a given wash tub.

50 The invention possesses other objects and features of advantage, some of which, with the foregoing, will be made manifest in the following description of the preferred form of the invention which is illustrated in the drawings accompanying and forming part of the specification. It is to be understood

that it is not intended to limit the invention to the embodiment shown by the said drawings and description as variations may be adopted within the scope of the invention as 60 set forth in the claims.

Referring to the drawings:

Fig. 1 is an end elevation and partial section of a form of the invention as adapted to an ordinary domestic cement or other 65 laundry tub.

Fig. 2 is a front elevation of the applied laundry mechanism mounted upon a wash tub which is shown in vertical section.

The present invention concerns that type 70 of washing machines deriving power from small electric motors operative thru a suitable train of gears to drive elements arranged in a tub or tank and which reciprocate upon a batch of clothes or pieces in the 75 tank to be washed and which reciprocating elements act to compress and then release the material being washed. To facilitate the washing effect on the material or pieces, a 80 feature of the present invention is a yielding false bed or bottom preferably perforated and of corrugated form upon which the material within the tank rests in a position well above the bottom of the tank, thus allowing the collection of sediment at the bottom as it is washed from the laundry.

A further important feature of the invention is the arrangement of the driving mechanism of the washing elements upon a lid 85 or cover of the tub or tank, as the case may be, thus providing an organized unit movable as a body from and to operative position.

In Figs. 1 and 2 inclusive the invention is 90 shown as incorporated in a washing machine including a box, or tank 35 having a bottom 4 above which is spaced a false bottom 5. The false bottom serves not only for the purpose of supporting the material therein being washed, but also, facilitates in the washing action upon the material. This action is enhanced by providing a false bottom of comparatively roughened top surface as indicated by the corrugations 7. It is understood that any foraminous construction of bottom 5 may be employed. Preferably the bottom 5 is yieldingly mounted as by being supported upon springs 8.

The tank is provided with a cover 10 preferably hinged. The cover is provided with 110 a crank shaft 13 journaled in bearings and having connecting rods 15 which sweep in

2
apertures provided therefor in the cover 10. Pivottally connected to the lower ends of the connecting rods 15 are plunger devices which preferably, are maintained in 5 horizontal position, while they are reciprocated by suitable guides, as for instance, rods 16 extending upwardly from the plungers and sliding in guide tubes 17. These tubes are firmly mounted in the cover 10 and 10 project downwardly therefrom.

To secure effective action of the plungers referred to, these preferably include a frame 18 within which is arranged a rigid grid of suitable construction. The plungers may be 15 of any desired proportion and in their lowermost positions leave a considerable space above the false bottom 5 upon which the material being washed will be compressed by downwardly moving plungers; the false bottom 20 5 yielding under the pressure and automatically returning to normal position under the reaction of the springs 8. The cranks of the shaft are set in opposed relation and the plungers therefore act alternately, first at 25 one end and then at the other end of the tank.

While power may be transmitted to the crank shaft 13 in any desired manner, it is here shown as provided on one end with a 20 gear 20, engaging a reduction gear driven by a motor shaft 27.

There is shown a form of the invention in which the organization is adapted to be mounted bodily as a unit upon a 35 domestic laundry wash tub 35, which is shown as provided with the cover 10 hinged at one side corner of the tub as at 11 so that the cover may be tilted upwardly. The top edges of the end panels of the tub are shown 40 as covered by channel strips 36 one of which provides for the connection of hinge 11 and the other of which is shown as provided with a suitable latching device 32 to hold the cover 10 down when the washing apparatus is in operative position. The guard channels 36 may be readily applied and easily removed and are adapted to be clamped in place by means of set or wing screws 37.

50 In this form of the invention the motor and the shaft 27 are mounted directly upon the cover 10 and operate through a train of

gears to drive the gear 20 and the crank shaft 13, the cranks of which are connected to the connecting rods 15 driving the plungers 18 which as above described, are guided for vertical movements by the guide rods 16 and the fixed tubes 17.

55 From the above it will be seen that when the invention is organized as a unit to be applied to the ordinary domestic washing tub, the motor and the associated parts are all mounted directly upon the cover 10 of the tub, and this latter can be moved to full open position carrying the plungers out of the way, all without disconnecting or removing any of the organized parts from their relative positions.

60 During the operation of the machine the reciprocating plungers 18 each alternately compress and then release the laundry or the material being operated upon, so that the water surges freely to and fro through the material, all of the sediment that is washed out passing through the perforated or foraminous false bottom 5, which by reason of its rough upper surface facilitates in the 65 washing of the clothes or material and prevents the same from playing in the dirty water in which the sediment is collected below the false bottom 5.

70 What is claimed is:

75 1. A washing machine including a tub having a cover, a crank shaft mounted on the cover, fixed guides extending down from the 80 cover of the tub, plungers arranged below the cover and connected to said shaft for intermittently subjecting material on said bottom to compression, and guides connected to the plungers and operating in the fixed 85 guides.

90 2. A washing machine including a tank having a cover, a crank shaft mounted on the cover, a plurality of guide tubes extending down through the cover of the tank, 95 plungers arranged below the cover, pitmans pivotally connected to the plungers below the cover and to said shaft for intermittently subjecting material on said bottom to compression, and guide rods fixed to the plungers and operating in said tubes.

100 In testimony whereof, I have hereunto set my hand.

SAMUEL B. CALDWELL.
